UNITED STATES PATENT OFFICE

CLAUDE N. BIELENBERG, OF DEER LODGE, MONTANA

CONCENTRATING MACHINE

Application filed May 31, 1928. Serial No. 281,937.

This invention relates to improvements in concentrating machines of that type which are especially adapted to the separation of finely divided and wet pulps, and which employ a traveling endless belt on which is effected the separation of the worthless gangue from the valuable mineral contents.

The primary object of the invention is to provide a concentrating machine of the above kind which is extremely simple in construction and adapted to most efficiently effect separation of the mineral from the gangue.

Another object is to provide an improved concentrating machine of the above kind having simple and efficient means for readily adjusting the lateral inclination of the endless belt, whereby to secure most efficient operation under various conditions of use.

Other objects will appear as the nature of the invention is better understood, and the same consists in the novel form, combination and arrangement of parts hereinafter more fully described, shown in the accompanying drawings and claimed.

In the drawings:

Figure 1 is a top plan view of a concentrating machine embodying the present invention.

Figure 2 is an elevational view thereof, partly broken away and in section.

Figure 3 is an enlarged end elevation looking toward the right of Figure 1, with parts broken away and in section.

Figure 4 is an enlarged fragmentary tail elevation looking toward the right of Figure 3.

Figure 5 is a fragmentary sectional view of the belt; and

Figure 6 is a fragmentary perspective view illustrating a manner of mounting the lower ends of the cross timbers on the base frame.

Referring more in detail to the drawings, the present concentrating machine embodies a suitable open substantially rectangular base frame 5 upon which is adjustably mounted a supplemental frame 6 having a head roller 7 and a tail roller 8 journaled therein around which passes an endless traveling belt 9, the rollers 7 and 8 being respectively mounted at opposite ends of the frame 6 as shown

clearly in Figures 1 and 2. The rollers 7 and 8 have shafts suitably journaled in bearings 10 carried by the longitudinal rails of the frame 6, and the bearings for the shaft of the tail roller 8 are preferably adjustable longitudinally of the machine in order to adjust the tension of the belt 9 in an obvious and well known manner.

The frame 6 has corner uprights or legs 11 secured at their lower ends upon cross timbers or bars 12 whose ends, adjacent one side of the machine are loosely mounted upon the adjacent longitudinal rail of the base frame 5 so as to be capable of vertical swinging movement for adjustment, although restrained from longitudinal or lateral shifting. This may be accomplished in any suitable way but is shown as effected by providing the adjacent longitudinal rail of the base frame 5 with pairs of upwardly projecting pins 13 loosely extending through in apertures in cross pieces 14 provided on the adjacent ends of the cross bars 12 as shown in Figures 1 and 6. The other ends of the cross bars 12 at the opposite side of the machine are provided on their undersides with wedge blocks 15 having inclined lower edges, and slidably mounted in bearings 16 upon the outer side of the adjacent longitudinal rail of the base frame 5 for movement longitudinally of the machine. A rod 17 which carries further wedge blocks 18 having inclined upper edges and cooperating with the respective wedge blocks 15 whereby to adjust the lateral inclination of the frame 6 and the belt 9 upon longitudinal adjustment of the rod 17 and its wedge blocks 18. This construction is more particularly shown in Figures 3 and 4, and in order to facilitate manual longitudinal sliding adjustment of the rod 17, a rack bar 19 is fixed to the latter intermediate its ends for actuation by a pinion segment 20 which meshes therewith and is carried by a hand lever 21 pivoted as at 22 to the base frame 5 above the rack bar 19. As indicated in Figure 3 and clearly shown in Figure 5, the edge of the belt 9 at the higher side of the machine is provided with an inwardly projecting continuous flange 23 adapted to engage the edges of the rollers 7 and 8 at

the higher side of the machine whereby the belt is prevented from slipping sidewise toward the lower side of the frame 6.

At the receiving end of the belt is provided a supply launder 24 which discharges into the feed box 25 arranged along the upper edge or side portion of the belt 9 and provided with discharge openings 26. The feed box 25 preferably forms a partitioned continuation of a clear water box 27 extending along the upper side edge portion of the belt and provided with discharge openings 28. The wash water is supplied to the clear water box 27 from any suitable source by the water supply pipe 29.

Beneath the belt 9 at the tail end of the machine is arranged a transverse water pipe 30 having suitable perforations through which the water discharges in jets upon the belt 9 at the underside of the tail roller 8, to thereby wash the concentrates from the belt into a concentrate box 31 suitably placed and supported at the tail end of the belt. Suitable means is provided for actuating the belt from the tail roller 8, and as shown said roller is provided with a drive wheel or gear 32 adapted to be suitably connected to any suitable source of power.

The operation of the machine is as follows:

The belt travels in the direction of the arrow *a* of Figure 1 from the head roller to the tail roller, and the pulp or material to be concentrated is discharged from the openings 26 in the feed box 25 onto the belt 9. The forward travel of the belt causes the pulp to take a diagonal course across the belt in the direction indicated by the arrow lines *b* in Figure 1, toward the catch launder 33. The heavier matter at once settles on the belt, while the balance flows off into the tailing or catch launder 33. The forward travel belt carries the material opposite the fresh water box 27 from which the fresh water washes off the materials of lighter specific gravity into the catch launder 33, leaving the valuable and heavier material attached and clinging to the belt 9. The travel of the belt 9 continues to carry forward the clinging and adhering mineral onto and over the tail roller 8 where it eventually is washed from the belt into the concentrate box 31 by the jets of water from the pipe 30. The above operation is uniform and continuous, and the amount of worthless gangue rejected can be increased by varying the inclination at which the belt lies, by varying the amount of fresh water supplied for washing, or by varying the speed at which the belt is caused to travel.

Minor changes may be made without departing from the spirit and scope of the invention as claimed.

What is claimed as new is:

65 In an ore concentrating machine, the com-

bination of a base frame and a supplemental frame, a concentrating table mounted on the base frame, and means associated with the base frame and the table for adjustably laterally tilting said table, said supplemental frame having legs, transverse bars upon which the lower ends of said legs are secured, said transverse bars having corresponding ends pivotally resting upon a longitudinal member of the base frame at one side of the machine, said second named longitudinal member of the base frame having pairs of spaced upwardly projecting pins, and cross pieces on the adjacent ends of said transverse bars having apertures through which said pins loosely project.

In testimony whereof I affix my signature.

CLAUDE N. BIELENBERG.
